UNITED STATES PATENT OFFICE.

LEWIS A. FRITSCH, OF CINCINNATI, OHIO.

FABRIC FOR ATHLETIC BELTS.

1,119,944.

Specification of Letters Patent.

Patented Dec. 8, 1914.

Application filed February 5, 1912. Serial No. 675,638.

To all whom it may concern:

Be it known that I, LEWIS A. FRITSCH, a citizen of the United States of America, and resident of Cincinnati, county of Hamilton, and State of Ohio, have invented 5 certain new and useful Improvements in Fabric for Athletic Belts, of which the following is a specification.

My invention relates to fabrics for use in 10 the athletic belts which ordinarily are termed "jockey straps."

The object of the invention is to provide 15 a fabric, which is adapted to the particular needs of the pouch or bandage portion of a jockey strap, namely, which will afford the proper support with the least discomfort to the wearer.

In order to disclose the nature of my invention, and the manner of its use, I have 20 illustrated it in use in a belt which consists of a circular elastic band or strap 4, a pouch or bandage portion 5, which is substantially V shaped and is secured along its upper edge to the strap 4, and at its lower 25 end or apex to elastic back straps 6 and 7, which extend rearwardly and upwardly and are secured at their rear ends to the strap 4 as is customary with such belts.

The pouch or bandage portion 5 embodies 30 my present invention and, as illustrated, is formed of specially knit material of such character that the pouch is capable of yielding or stretching sufficiently to conform to the shape of the parts supported by it and 35 yet is capable of holding the parts in the proper positions without binding or exerting too much pressure on them. This is accomplished by providing an elastic selvage along the converging edges of the bag and 40 by providing a peculiar stitch for forming the central or supporting portion of the bandage. The elastic converging edges of the portion 5 are reinforced by rubber or other elastic strips 8 which are suitably 45 threaded through the fabric so that they are held in place on it. A comparatively wide margin 9 is formed along each elastic edge, which is so formed that it is capable of being greatly extended in a direction parallel 50 to the edge but will yield a comparatively small amount in a direction at right angles to the edge.

The selvage 8 is of a plain knit interwoven with rubber strands. Sections 9 are 55 a plain knit stitch. Sections 13 are a plain knit stitch crossed every third course. In

sections 12 there is one course of plain stitch, one course of tucked stitch crossed to the left, and then one course of plain stitch. In sections 11 there is one course 60 of plain stitch, one course tucked stitch crossed to the right, and one course of plain stitch. Between each of the sections 12 and its adjacent sections there is one tucked stitch crossed and then reversed. The knitting 65 is a continuous operation starting with the selvage 8, then one of the sections 9, then the adjacent section 13, then the section 12, then section 11, and then the remaining sections 12, 13, 9 and the selvage 8 successively.

A belt of the character illustrated provided with a fabric formed as described and having the elastic selvage is particularly effective, since this elastic holds the edge 75 of the fabric against the body, and the central portion of the fabric yieldingly holds the parts, supported by it, in the proper positions.

In the drawings I have illustrated the 80 bandage 5 as provided with two converging sections 13 of porous structure which extend substantially parallel to the selvage edges of the bandage and located between the marginal sections 9 and the tucking 35 weave sections 10.

The sections 13, like the strips 10 are formed continuously with the remainder of the cloth and are of an open mesh and flimsy structure which is capable of readily conforming to the shape of the parts supported by the portion 5, and also provides a circulation of air to the parts covered by the belt. It will be noted that the sections 13 are located at the points where the circulation 90 is most effective and also where the least supporting force is needed. In addition to this the location is such as to permit the more substantial sections 10 to bulge 95 outwardly to form a bag-like pouch which is fullest about a third of the way up from the apex of the portion 5.

In the drawings I have shown the portion 5 provided with a non-extensible piece of tape 14 which is secured to the cloth and projects forwardly from the apex midway between the converging edges. This tape is provided for the purpose of stiffening and strengthening the lower end of the portion 105 5 and for insuring a better connection between it and the back straps 6 and 7.

The difficulties encountered with most

belts of the character described is that, they do not combine the necessary qualifications so as to produce a belt, which is at once comfortable and effective in operation. If the 5 pouch portions 5 of the belts are substantial enough to provide the proper supporting qualities they are usually non-porous and are not capable of conforming to the shape of the parts supported; and if they are capable of conforming to the shape of the 10 parts supported they are so flimsy that they are ineffective as supports.

The combination of the elastic selvage, 15 the marginal strips 9—which are capable of yielding longitudinally, more than they are capable of yielding laterally, and the open mesh flimsy structure of the strips 13, in connection with the strips 10—of substantial 20 weave, produces an athletic belt, which combines the necessary qualities of such a belt and does not possess any of the 25 objectionable features.

In accordance with the patent statutes I 30 have illustrated the preferred form of my invention and described its construction and its principal features, but I desire it to be understood that various changes, modifications and substitutions may be made without departing from the spirit and the scope 35 of my invention as set forth in the appended claims.

What I claim is:

1. A fabric comprising an elastic selvage 40 and a central portion formed of a series of sections between which is a tuck stitch 45

crossed and then reversed, said sections being made of alternating courses of plain stitching and tuck stitching.

2. A fabric comprising an elastic selvage and a central portion made of three sections, 40 said sections being made of alternating courses of plain stitching and tuck stitching, the tuck stitching in the central of said sections being crossed in the opposite direction from which the tuck stitching in the other 45 two sections are crossed.

3. A fabric comprising elastic selvage, marginal sections adjacent the selvage and composed of plain knit stitches, and a central portion consisting of a series of sections 50 each section of said series being composed of alternating courses of plain stitches and tuck stitches.

4. A fabric comprising elastic selvage, marginal sections adjacent the selvage and 55 composed of plain knit stitches, a central portion consisting of three sections each of the sections of the central portion being made of alternating courses of plain stitches and tuck stitches, the tuck stitches of the 60 central of said courses being crossed in a direction opposite to the direction in which the cross stitches of the other of said sections are crossed, and the sections of said 65 central portion being connected by a tuck stitch crossed and then reversed.

LEWIS A. FRITSCH.
